UNIT INJECTOR PUMP WITH PILOT INJECTION

John J. May, Birmingham, Mich., and Ray C. Ulrey, Spring Hill, Ala., assignors to General Motors Corporation, Detroit, Mich., a corporation of Delaware

Application August 12, 1955, Serial No. 528,039

6 Claims. (Cl. 103—41)

This invention relates to unit injector pumps such as are used for delivering metered amounts of fuel to internal combustion engines, and particularly to such devices wherein the injection is effected in two distinct phases, i.e., a "pilot" or primary injection and a "main" or secondary injection with a "gap" or time interval therebetween.

Injection of the fuel in this manner is advantageous, particularly with diesel engines, because the primary injection charge which can be made relatively small in quantity serves to initiate the combustion in the engine cylinder in advance of the main charge, thereby reducing the rate of pressure rise and the peak pressure developed in the combustion chamber, with consequent increased efficiency and lowering of the noise level of the combustion process. While prior unit fuel injector pumps of this general type have heretofore been proposed, they have been subject to a number of objections including an inability to precisely time one or both of the injection charges and have generally been of unduly complicated design with attendant excessive cost of manufacture.

It is the object of our invention to overcome the objections of such prior injector pumps by providing that the pumping chamber pressure be at or higher than the primary injection pressure during the gap between injections, by providing for both injection charges to be delivered from the pumping chamber through a common passage means to the injector nozzle, and by further simplifying the design of the unit through the use of a pump plunger and cylinder having a minimum of cooperating ports and passages for controlling the start and end of the successive injector charges.

Further objects of the invention will be apparent from the following description of one preferred embodiment thereof, wherein:

Figure 1 is a longitudinal sectional view through a unit fuel injector pump assembly constructed in accordance with the invention.

Figure 2 is a diagrammatic view showing a full 360° development of the inner end portion of the plunger of the pump of Figure 1.

Figures 3-8 are fragmentary views of the pump plunger and cylinder members in their various relative positions during the pumping stroke.

The injector pump shown in Figure 1 includes the pump body 2 having a lower removable portion threaded thereto at 4 and adapted to extend through an opening in the cylinder head of a diesel engine so as to locate the fuel nozzle 6 at its lower end within the combustion space of the engine. Small spray orifices 8 in the tip end of this nozzle are supplied by a fuel duct 10 which is normally closed by a spring biased delivery valve 12 which opens under predetermined injection pressures developed in the fuel chamber 14 of the pump. Holding the nozzle 6 seated in the lower end of the housing are

2

upper and lower spacer blocks 13, 15 with connecting passages 16 and 18 and a pump cylinder member in the form of a bushing 20 which has a shoulder 22 abutting the lower end of the upper body part 2. The upper spacer block 13 closes the lower end of the bushing. The upper end of the bushing is of reduced wall thickness and extends into the body part 2 and locates a pinion 24 therein between a spacer sleeve 26 and a ring 28 which is seated against a shoulder in the body 2. The bore 30 of the bushing is slidably fitted by a pump plunger member 32 whose lower or inner end cooperates with the bushing bore in defining the pumping chamber 14, and whose upper end has a poly-sided section 34 slidably splined in the pinion 24. Reciprocation of the plunger is effected by an engine driven rocker 36 or like member which transmits its movement to the extreme outer end of the plunger by a push rod 38. The upper end of the push rod is flanged to receive return thrust from a guide sleeve 40 which slidably fits in the upper end of the pump body 2 and is biased therefrom by a compression spring 42. The lower end 44 of the guide sleeve 40 is bifurcated to interengage a necked-in portion 46 adjacent the upper end of the plunger. Meshing with the pinion 24 is a fuel rack 48 which is suitably guided for actuation transversely of the plunger to rotatively adjust the plunger for controlling the duration and timing of the fuel injection charges during engine operation.

Fuel supply and return passages, one of which is shown at 50, are provided in the pump body for connection with a transfer pump or other pressure fuel source (not shown). These passages lead to and from a fuel receiving chamber 52 which is formed as an annular space surrounding the bushing 20. Passage means are provided in this bushing for connecting its bore 30 with the fuel receiving chamber 52 and the passage 18 leading to the fuel nozzle 6. Included in this passage means are inlet and by-pass ports 54, 56 which extend through opposite side walls of the bushing in spaced relation axially thereof as shown, a fuel discharge port 58 diametrically opposite the port 56 and connected by a longitudinal "tip" passage 60 with the passage 18, and a small bleed by-pass port 62 which extends through the side wall of the bushing to connect the receiving chamber with the bore 30 at a distance inwardly from the ports 56 and 58. This bleed port 62 is of substantially smaller size than the discharge port 58, as shown.

Passage means are provided in the plunger to cooperate with the cylinder ports 54, 56 and 58 in controlling the start and ending of the main fuel charge. Such passage means includes an external metering groove 64 which encircles the plunger at a distance above its innermost end, together with transverse and connecting axially drilled ports 66 and 68 which continuously connect the metering groove with the pumping chamber 14. The metering groove 64 is defined by axially spaced inner and outer lands 70 and 72 which are best shown in the diagrammatic development of this end of the plunger in Figure 2. Indicated in broken outline in Figure 2 are also the relative locations of the cylinder ports 54, 56, 58 and 62, when the plunger is at the start of its pumping stroke and is angularly rotated to its maximum pumping rate setting by the fuel rack 48.

Referring to Figure 3 which also shows the plunger in this same position at the start of its pumping stroke, it will be seen that fuel from the receiving chamber 52 may flow into the pumping chamber 14 directly via the ports 56 and 62, and via the port 54 through the plunger metering groove 64 and passages 66, 68. During the initial downward movement of the plunger to the posi-

tion shown in Figure 4, excess fuel and any air contained in the pumping chamber 14 is displaced or by-passed through the ports 54 and 56 until the inner extremities of the outer and inner lands 72 and 70 close off the ports 54 and 56, respectively, without creating sufficient pressure in the pumping chamber to open the delivery valve 12 to effect injection. A small amount of fuel also is by-passed through the bleed passage 62 to the receiving chamber during this portion of the plunger travel. The discharge port 58 being still partially uncovered by the inner land at this point, the initial or primary injection then begins at a rate and pressure reduced slightly by the bleed passage 62 being still allowed to bypass some of the fuel to the receiving chamber. Such primary injection continues until the plunger reaches its position shown in Figure 5, when the discharge port becomes fully closed by the inner land of the plunger. This results in an immediate cut-off of further delivery of the fuel to the nozzle, without relieving the pump chamber pressure. A "gap" thus occurs during which there is no injection until the plunger reaches the position shown in Figure 6 when the inner land starts to again uncover the discharge port. Fuel under pressure in the pumping chamber is then displaced through the plunger passages 66 and 68 to the metering groove 64 for delivery via the discharge port to the fuel nozzle, the fuel by-pass and inlet ports 56 and 54 in the bushing remaining closed by the plunger inner and outer lands 70, 72, respectively. "Main" or secondary injection then begins and continues until the plunger reaches the position shown in Figure 7 when the port 56 begins to become uncovered by the inner land 70, resulting in fuel in the pumping chamber being by-passed via the plunger passages 66, 68 and port 56 to the receiving chamber. It will be noted that simultaneously with, or immediately following the start of the secondary injection, the bleed passage 62 is covered by the plunger inner land, augmenting the rate and pressure of the secondary fuel injection. Figure 8 shows the plunger in its innermost position at the end of the pump chamber, with the by-pass port 56 still in communication with the pumping chamber via the metering groove and plunger passages. On the return stroke, fuel under the pressure maintained in the receiving chamber flows into the pumping chamber through the cylinder ports 54 and 56 as they make registry with the plunger metering groove.

Referring again to Figure 2, it will be seen that rotation of the plunger in the direction of the arrow 80 results in delaying both the start and ending of the primary fuel injection period, as well as the start of the secondary injection. This is by reason of the inner and outer extremities 82 and 84 of the inner land and the outer extremity 86 of the outer land being inclined in the same direction to the plunger axis, whereby the closure of the port 54 and closure and reopening of the discharge port 58 are successively delayed. That portion 88 of the inner land outer extremity which controls the opening of the by-pass port 56 is shown extending normal to the plunger axis so that the start of the secondary injection may be advanced or retarded relative to the termination thereof, thereby enabling the duration of this secondary injection charge to be varied by rotation of the plunger. Since the primary injection timing only need be varied, and not its duration, and since its advancement and retardation may be equal to that of the main charge, the inclination of extremities 82 and 86 are equal and in the same direction to the plunger axis as the inclination of 84. Locating the by-pass port 56 diametrically opposite the discharge port enables the latter to be drilled through the port 56, thus obviating the need for plugging an access hole for the drill on the discharge port side of the bushing. Proper timing of the uncovering of the by-pass port 56 so aligned with the discharge port requires only extending the inner extremity 70

of the plunger inner land 70 on the side thereof facing the port 56. Also, the herein described arrangement of cylinder ports, plunger metering groove and passages, enables the provision of but a single discharge port 58 and its connecting passage to the nozzle.

While only a single preferred embodiment of the invention has been disclosed, it is appreciated that numerous minor changes in the construction and arrangement of the parts may be made without departing from the spirit and scope of the invention as defined in the following claims.

We claim:

1. In an injector pump, a pump cylinder closed at one end, means defining a fluid receiving chamber externally of the cylinder, two ports axially spaced from each other and from said closed end along the cylinder axis and connecting the interior of the cylinder with said receiving chamber, a fluid injection nozzle, a fluid discharge port connecting the nozzle with the interior of the cylinder at a distance axially thereof intermediate said closed end and the more remote of said two ports from said closed end, a plunger operable in said cylinder having two axially spaced lands slidably fitting the internal side walls of the cylinder to control the passage of fluid through said ports and an internal passage connecting the inner end of the plunger with the space between said lands, the relative spacing of said lands and ports being such that during movement of the plunger in its pumping direction said two ports are closed in advance of closing said discharge port to initiate a primary injection, after which the inner land traverses over the discharge port while said two ports remain closed to first terminate said primary injection without decreasing the chamber pressure and then initiate a secondary injection through said passage and discharge port when said passage and discharge port are in communication, the more adjacent of said two ports to said closed end of the cylinder being then subsequently uncovered by the inner land to terminate said secondary injection.

2. The injector pump defined by claim 1, wherein the more adjacent of said two ports to the closed end of the cylinder is diametrically opposite said discharge port, and the outer extremity of said inner land on the side facing said more adjacent port is extended toward the inner end of the plunger to delay the uncovering of said more adjacent port by said inner land during the plunger pumping movement after said inner land has uncovered the discharge port.

3. The injector pump defined by claim 1, wherein the plunger is axially rotatable and the inner and outer extremities of said inner land on the discharge port side of the plunger are inclined to the plunger axis, whereby rotation of the plunger relative to the cylinder varies the timing of both the termination of said primary injection and the initiation of said secondary injection.

4. The injector pump defined by claim 3, wherein the inner extremity of said outer land on the side of the plunger facing said more remote port is parallel with said inclined inner land inner extremity, whereby rotation of the plunger relative to the cylinder varies the timing of initiation of said primary injection equally with its termination.

5. The injector pump defined by claim 1, wherein the cylinder has a bleed port of smaller capacity than said discharge port and connecting said fuel receiving chamber with the interior of the cylinder at a distance axially thereof toward said closed end from the discharge port for closure by said inner land only after said discharge port is closed during the plunger pumping movement.

6. In an injector pump, a pump cylinder closed at one end and having an inlet port and a discharge port, said ports being spaced from each other and from said closed end, a plunger operable in said cylinder having two axially spaced lands slidably fitting the internal side walls of the cylinder to control the flow of fluid through said

ports and a passage connecting the inner end of the plunger with the space between said lands, the relative spacing of said ports and lands being such that during movement of the plunger in its pumping direction said inlet port is closed in advance of closing said discharge port to initiate a primary injection, after which the inner land traverses over the discharge port while said inlet port remains closed to first terminate said primary injection without decreasing the chamber pressure and then initiate a secondary injection through said passage and discharge port when said passage and discharge port are in communication, said inlet port being then subsequently uncovered by the inner land to terminate said secondary injection.
